UNITED STATES PATENT OFFICE

CLIFFORD OLDEE, OF WILMETTE, ILLINOIS

EXPANSION JOINT

Application filed January 17, 1931. Serial No. 509,815.

My invention relates to expansion joints and more particularly to metallic expansion joints for concrete floors, pavements, and the like.

5 The concrete pavements as shown by the prior art are, as a rule, constructed in a plurality of sections with cracks or spaces between the sections, and with substantially larger spaces located at regular intervals for 10 the purpose of permitting longitudinal expansion of the pavement under changes of temperature of the atmosphere. When the sections of the pavement expand, there is a gradual sliding of the sections toward the 15 larger expansion joint, but when the sections subsequently contract they do not return to their former positions, with the result that the relatively wide expansion space is smaller and soon disappears, the space being divided 20 among the plurality of smaller cracks or spaces formed between the adjacent sections of the pavement and it is practically impossible to prevent this action of the pavement sections in closing up the larger expansion space.

25 The open expansion spaces between adjacent sections soon becomes filled with dust, soil, floor sweepings or sand particles and as this material is generally incompressible it follows that when expansion again takes place, the joints can not close between the adjacent sections and the whole series of sections is pushed still further toward the 30 larger expansion space until eventually all of the cracks, including the larger expansion space, become filled with hard packed unyielding material. The purpose of the original large expansion space is then defeated and further expansion of the concrete sets 35 up compression stresses as great as would be the case had no expansion spaces been provided in the first place.

40 One of the objects of this invention is the elimination of the foregoing disadvantages of prior constructions by the provision of an improved expansion joint of relatively simple and economical construction, which is adapted to permit relative movement between adjacent pavement sections, and to 45 prevent the filling of cracks or spaces between

the sections with dirt or other foreign material.

Another object of this invention is the provision of an improved expansion joint assembly including a simplified form of expandible member including a substantially V-shaped laterally expandible portion and anchoring flanges for securing the same in place along the adjacent pavement sections.

Another object is the provision of an improved expansion joint including an improved expandible member in combination with a division plate for supporting the expandible member and for insuring the formation of separate sections of pavement, and means for anchoring the division plates in vertical position during the formation of the sections.

Other objects and advantages of my invention will appear from the following description.

In the accompanying drawings,

Fig. 1 is a vertical sectional view of a portion of a concrete pavement which is provided with an expandible joint of a type incorporating my invention;

Fig. 2 is a view similar to Fig. 1 but showing the adjacent sections of the pavement contracted as in cold weather and drawn away from each other;

Fig. 3 is a view similar to Fig. 1 but disclosing a slightly modified form of my invention;

Fig. 4 is a perspective view of fragments of my invention shown disassembled;

Fig. 5 is a view similar to Fig. 3 showing a slight modification therefrom;

Fig. 6 is a view similar to Fig. 1 but illustrating another modification of my invention; and

Fig. 7 is a side elevation of the metal parts shown in Fig. 6.

While in the drawings I have illustrated my invention as applied to a concrete pavement, it will be understood that my invention may be utilized in practically all forms of pavement or other monolithic construction in which it is desirable to provide expansion joints between portions which are cast or molded in place for the purpose of prevent-

ing the filling of cracks or spaces therebetween with foreign material.

In the drawings, numerals 5 and 6 designate adjacent portions of concrete sections of a pavement which abut a division plate 7 extending across the pavement. The expandable member 8 preferably comprises a strip of non-corrosive flexible sheet metal which is formed with a central portion 9 depressed 10 forming a substantially V-shaped corrugation to allow for expansion by partially flattening as illustrated in Fig. 2. The member 8 also includes anchoring flanges 11 and 12 extending laterally into the concrete.

15 The V-shaped corrugation or groove 9 expands longitudinally of the flexible strip 8 and is formed with an easy curve 14 at the apex to facilitate repeated bending without cracking of the metal. The diverging sides 20 15 and 16 of the V-shaped portion are joined to downwardly extending side members or flanges 17 and 18 at 19 and 20. The lower ends of flanges 17 and 18 are formed integral with the anchoring flanges 11 and 12.

25 Although the anchoring flanges may be made in various forms, I have illustrated them including return-bent flanges 21 and 22 for engaging the concrete and preventing the withdrawal of the expansion member 8. The 30 division plate 7 not only permits ready separation of the sections of the concrete but supports the expansion strip 8 prior to the pouring of the concrete, it being secured preferably by welding at 25 to the outer side of 35 spaced lugs or flanges 26 struck from the flange 11 and depending from the side flange or portion 17 best shown in Fig. 4. The upper adjacent corners 27 and 28 of the concrete are preferably rounded off to a surface substantially flush with the inner surface of 40 the diverging portions 15 and 16 of the V-shaped groove to protect the corners 19 and 20 and prevent injury to the expandable member by traffic.

45 In the normal use of my improved expandible joint, after the concrete has set, a decrease in temperature causes contraction of the adjacent sections 5 and 6 and they move apart as shown in Fig. 2, making a space 29 which 50 is protected at the top by the V portion 9 in which dirt or sand designated at 31 may collect. The bottom portion 14 will rise sufficiently to provide for the necessary contraction of the concrete. The space 29 being 55 kept clear of foreign matter, it may be again taken up by the concrete when the sections again expand and without setting up undue stresses.

In Fig. 3 the division plate extends along 60 the inner side of the portion 17 and is preferably spot welded at 35 above the flange

11. In this construction the depending flanges 26 of Fig. 1 are eliminated. In Fig. 3 the flanges 11 and 12 have small vertically 65 extending flanges 36 and 37 which help to

anchor the flanges 11 and 12 in the concrete.

In Fig. 5 the division plate also extends upwardly along the inner side of the flange 17 forming a reinforcement for the same, and it is secured at 38 to the depending flanges 70 26. In this modification the flanges 17 and 18 are shorter than that shown in Fig. 3, for the purpose of facilitating the welding of the parts together. The flanges 11 and 12 in this modification are provided with downwardly turned marginal flanges 41 and 42 which are anchored in the concrete sections 5 and 6.

75 In the modification of my invention shown in Figs. 6 and 7 the expandible member is substantially like that shown in Fig. 4 and is fixed preferably by welding at 25 to a division plate 43 which has upper and lower vertical portions 44 and 45 and an offset corrugation comprising a vertical portion 46 and inclined portions 47 and 48 connecting it to the vertical portions 44 and 45. The inclined portions or flanges 47 and 48 are provided with apertures through which may be inserted pins 49 for holding the plates in 80 position prior to the pouring of the concrete. The pins are placed through the plate 43 only at places adjacent points of attachment of the plate to the flanges 26, to avoid the possibility of the flanges interfering with 85 the driving of the pins.

90 The plate 43 as illustrated in Fig. 7 is arched to conform to the cross contour of a pavement, and the member 8 being flexible is bent to the contour of the upper edge of 95 the plate 43 and welded to the same.

99 It will be understood by those skilled in the art that modifications may be made without departing from the principle of this invention and I desire to avail myself of such 100 modifications and changes which come within the scope of the appended claims.

I claim as my invention:

1. A pavement or the like comprising a pair 110 of sections having adjacent edges, means for connecting said sections and preventing filling the spaces between the edges, comprising a flexible sheet metal member having a substantially V-shaped corrugation extending longitudinally of the adjacent edges of the 115 sections, integral anchoring flanges extending into said pavement sections and formed on each side of said V-shaped corrugation, said pavement sections having upper adjacent corners formed with surfaces substantially flush with the inclined surfaces 120 of the V-shaped corrugation, depending flanges on said flexible member, and a division plate fixed thereto and extending downwardly between the adjacent sections of the pavement.

2. A pavement or the like comprising a pair 125 of sections having adjacent edges, means for connecting said sections and preventing filling of a space between said edges, comprising

ing a flexible sheet metal member including an expandible portion and integral anchoring flanges formed along each edge and embedded in said pavement sections, depending 5 flanges on said flexible member and a division plate fixed thereto and extending downwardly between the adjacent sections of the pavement.

3. A pavement or the like comprising a pair 10 of sections having adjacent edges, means for connecting said sections and preventing filling of a crack between said edges, comprising a flexible metal member including an expandible central portion and laterally extending edges anchored in said sections, depending 15 flanges on said flexible member, and a division plate permanently fixed thereto and extending downwardly between the adjacent sections of pavement.

20 4. A pavement or the like comprising a pair 25 of sections having adjacent edges, means for connecting said sections and preventing filling of a crack between the edges thereof, comprising a flexible sheet metal member having a substantially V-shaped depressed corrugation 30 extending longitudinally of the adjacent edges, integral anchoring flanges formed on each side of said corrugation and extending into said pavement sections, and a division 35 plate interposed between said sections and being permanently welded to a side portion of said flexible member.

5. An expandible member for concrete 35 pavements and the like comprising an integral sheet metal strip of flexible material including a substantially V-shaped corrugation 40 extending longitudinally of said strip and adapted to expand laterally to permit relative movement between adjacent pavement sections, anchoring flanges carried by each side of said corrugated portion to be 45 embedded in adjacent concrete sections, and integral depending longitudinally spaced lugs carried by one side of the V-shaped portion adapted to be secured to a division plate.

6. A pavement or the like comprising a pair 50 of sections having adjacent edges, means for connecting said sections and preventing filling of a crack between the adjacent edges, comprising a flexible sheet metal member having a substantially V-shaped bend extending 55 longitudinally of said crack, integral anchoring flanges extending into said pavement sections and formed on each side of said 60 V-shaped bend, and a division plate comprising a sheet metal member extending along one side portion of said flexible member and securely and permanently fixed thereto and depending therefrom.

65 7. A pavement or the like comprising a pair 70 of sections having adjacent edges, means for connecting said sections and preventing filling of a crack between the adjacent edges, comprising a flexible sheet metal member having a substantially V-shaped bend extending 75 longitudinally of said crack, integral anchoring flanges extending into said pavement sections and formed on each side of said 80 V-shaped bend, and a division plate comprising a sheet metal member extending along one side portion of said flexible member and securely and permanently fixed thereto and depending therefrom, said division plate including a longitudinal corrugation having vertically aligned perforations therein for the reception of anchoring pins.

8. A pavement or the like comprising a pair 85 of sections having adjacent edges, means for connecting said sections and preventing filling of a crack between the adjacent edges, comprising a flexible sheet metal member having a substantially V-shaped bend extending longitudinally of said crack, integral anchoring flanges extending into said pavement sections and formed on each side of 90 said V-shaped bend, and a division plate comprising a sheet metal member including a portion extending vertically from one of said anchoring flanges to one edge of said V-shaped portion and secured to a side portion of the flexible member for reinforcing the same.

9. A pavement or the like comprising a pair 95 of sections having adjacent edges, means for connecting said sections and preventing filling of a crack between said edges, comprising a flexible metal member including an expandible central portion and laterally extending edges anchored in said sections, depending 100 flanges on said flexible member, and a division plate permanently fixed thereto and extending downwardly between the adjacent sections of the pavement, said division plate including a longitudinal corrugation 105 having vertically aligned perforations therein for the reception of anchoring pins.

10. A pavement or the like comprising a pair 110 of sections having adjacent edges, means for connecting said sections and preventing filling of a crack between the edges thereof, comprising a flexible sheet metal member having a substantially V-shaped depressed corrugation 115 extending longitudinally of the adjacent edges, integral anchoring flanges formed on each side of said corrugations and extending into said pavement sections, and a division plate interposed between said sections and being permanently welded to a side portion of said flexible member, said division plate including a longitudinal corrugation 120 having vertically aligned perforations therein for the reception of anchoring pins.

11. A pavement or the like comprising a pair 125 of pavement sections supported upon the subsoil and having adjacent edges, said sections being formed of portions of concrete placed adjacent each other, with an expandible sheet metal member having a flexible central portion and having a pair of anchoring flanges with integral portions embedded 130

in the concrete of the sections and anchored therein, said expandible member having downwardly extending flanges and a division plate welded to said downwardly extending flanges and adapted to form a division between said sections to permit movement between said sections.

In witness whereof, I hereunto subscribe my name this 24th day of December, 1930.

CLIFFORD OLDER.
